UNITED STATES PATENT OFFICE.

RICHARD RALPH BLOSS AND WILLIAM SCHWEMLEIN, OF PARKERSBURG, WEST VIRGINIA, ASSIGNORS TO THE PARKERSBURG RIG & REEL COMPANY, OF PARKERSBURG, WEST VIRGINIA, A CORPORATION OF WEST VIRGINIA.

DERRICK-FITTING.

1,385,659.

Specification of Letters Patent. Patented July 26, 1921.

Application filed October 2, 1920. Serial No. 414,240.

To all whom it may concern:

Be it known that we, RICHARD R. BLOSS and WILLIAM SCHWEMLEIN, citizens of the United States, residing at Parkersburg, in 5 the county of Wood and State of West Virginia, have invented certain new and useful Improvements in Derrick-Fittings, of which the following is a specification.

This invention relates to derrick fittings, 10 and it comprises a combination with the leg sections and horizontal girths of an angle iron derrick, of a pair of plates adapted to be secured to the ends of the girths, or to one of the girths or leg sections, said plates 15 being provided with curved flanges on their upper and lower edges adapted to receive and support the ends of the leg sections.

Derricks for oil rigs must be provided 20 with derrick fittings of simple construction that can be quickly put in place and removed when the derrick is being erected and disassembled. It is advantageous to provide a construction wherein the rig builder is not depended upon to properly adjust the parts 25 to obtain a symmetrical structure. A derrick fitting, to be satisfactory, should be constructed in the shop with the various openings for the reception of fastening means properly placed whereby the derrick, 30 when assembled, will produce a symmetrical structure.

In the present invention, we have provided a very simple form of derrick fitting for use in connection with angle iron derricks. The invention comprises a pair of plates which may be shop riveted to the girths or to one girth and one leg, the plates being provided with curved flanges for the reception of the ends of the leg sections. 35 The diagonal braces are secured to these plates by means of rotatable blocks having eccentrically arranged openings for the reception of the end of the brace. The parts may be properly assembled and the blocks 40 then rotated to tighten the braces as described in the co-pending application of Richard R. Bloss, Serial No. 414,241, filed October 2, 1920.

In the accompanying drawings, we have 50 disclosed one embodiment of the invention. In this showing—

Figure 1 is a side elevation of a portion of the derrick showing the derrick fitting in position.

Fig. 2 is a similar view at right angles to Fig. 1, and

Fig. 3 is a perspective view showing the parts detached.

Referring to the drawings, the reference numerals 1 and 2 designate the upper and lower leg sections respectively of a derrick. At the point where these leg sections are joined, the derrick is provided with horizontal girths 3 and 4 arranged at right angles to each other. The fitting comprises 60 a pair of plates 5 and 6. The plates may be secured to the girths, or as shown, one of the plates may be secured to the lower leg section and the other to a girth. Any suitable means may be employed for securing the 65 plates in position and we have shown them secured by means of rivets 7, the plates being riveted to the legs and girths in the shop, where the derrick is constructed thus reducing the amount of work to be done in the 70 field when erecting the derrick. The upper edges of the plates are provided with curved flanges 8 which receive the upper end of the lower leg section to transmit strains from the derrick structure above the fitting 75 to the leg section. The lower edges of the plates are provided with similar flanges 9 which receive the lower ends of the upper leg sections to transmit the strains to the fitting and thence to the lower leg sections. 85

As shown, the plurality of bolt holes 10 are provided in the plate 6, and the upper and lower leg sections are provided with bolt holes 11 and 12 respectively. Bolts 13 are arranged in these openings when the derrick 90 is assembled to secure the parts to each other. The bolts are provided with nuts 14 to retain them in position. A bolt opening 15 is provided in the plate 5 and the upper end of the leg section 2. The upper leg section 1 is provided with a bolt opening 16. When the derrick is assembled, the relation 95 of the various parts to each other is such that the bolt openings 15 and 16 are brought into alignment. Bolt 19 is passed through these aligned openings to secure the parts to each other, the bolt being provided with a nut 18. The girth 3 is secured to the plate 5 by means of bolts 17 passing through openings 20 and 21 in the girth and plate 100 respectively. The upper end of the diagonal brace 22 which extends from the next lower section of the derrick is provided with a 105

terminal 23 arranged at right angles and extending through an opening 24 in the plate 5. A cotter pin 26 is passed through an opening in the terminal to secure the end 5 of the brace in position.

The lower ends of the braces are provided with adjustable securing means whereby the braces may be tightened after the parts are assembled.

10 As shown, the end of the brace 27 which extends to the next section of the derrick fitting above is provided with a terminal 28 which is extended at substantially right angles and received in an eccentric opening 15 in rotating block 29. The block is arranged in an opening 30 in the fitting plate and is provided with an extension 31 having a handle 32. A ring 33 is arranged on the brace and is adapted to be slipped over the end 20 of the handle when the brace is tightened. The cotter pin 34 is arranged in the opening in the end of the brace to secure it in position.

25 In assembling a derrick, the parts are arranged with the various openings registering with each other and the bolts are placed in position. The handle 32 of the rotating block is turned substantially 180° and the end 28 of the brace is placed in position, the 30 upper end 23 having been previously secured in position and the cotter pin 26 placed in the opening in the upper end of the brace. After the various parts of the derrick have been assembled, the blocks are 35 rotated to tighten the braces and the rings 33 are slipped over the handles to retain them in a tightened position. The parts of the fitting are properly constructed so as to arrange the various openings to produce a 40 symmetrical structure when the derrick is assembled. It is merely necessary for the rig builder in the field to place the bolts in their proper positions and tighten them and then tighten the braces, the plates 5 and 6 45 being shop riveted to the derrick parts. The number of bolts to be used in erecting the derrick is reduced to a minimum and a very efficient construction is provided.

It is to be understood that while we have described the preferred embodiment of our 50 invention, various changes in the shape, size, and arrangement of parts may be resorted to without departing from the spirit of the invention or the scope of the subjoined claims.

Having thus described our invention, we claim:

1. A derrick fitting comprising a pair of leg sections and a pair of horizontal girths formed of angle iron, a plate secured to one 60 end of one of said girths, said plate being provided with a portion projecting beyond the end of the girth, a plate carried by one 65 end of one of said leg sections and projecting laterally therefrom, the other girth being adapted to be secured to said second plate, the ends of said leg sections being overlapped, and means for securing the overlapped ends to the projecting portion of said first plate.

2. A derrick fitting comprising a pair of leg sections and a pair of horizontal girths formed of angle iron, a plate secured to one 70 end of one of said girths, said plate being provided with a portion projecting beyond the end of the girth, the upper and lower 75 edges of the projecting portion of said plate being provided with oppositely arranged flanges, a plate carried by one end of one of said leg sections and projecting laterally 80 therefrom, the other girth being adapted to be secured to said second plate, the ends of said leg sections being overlapped and arranged on opposite sides of the projecting portion of said first plate with their edges 85 received in said flanges, and means for securing said overlapped ends to the projecting portion of said plate.

In testimony whereof we affix our signatures in presence of two witnesses.

RICHARD RALPH BLOSS.
WILLIAM SCHWEMLEIN.
